US00D909901S

(12) **United States Design Patent** (10) Patent No.: **US D909,901 S**
(45) Date of Patent: **** Feb. 9, 2021**

(54) **MOVEMENT SENSOR WITH CAMERA**

(71) Applicant: **AJAX SYSTEMS CYPRUS HOLDINGS LTD**, Nicosia (CY)

(72) Inventors: **Oleksandr Konotopskyi**, Kyiv (UA);
Ilshat Garipov, Haapsalu (EE)

(**) Term: **15 Years**

(21) Appl. No.: **35/508,034**

(22) Filed: **Aug. 2, 2019**

(80) **Hague Agreement Data**

Int. Filing Date: **Aug. 2, 2019**

Int. Reg. No.: **DM/204441**

Int. Reg. Date: **Aug. 2, 2019**

Int. Reg. Pub. Date: **Dec. 6, 2019**

(51) LOC (13) Cl. **10-05**

(52) U.S. Cl.

USPC **D10/106.7**

(58) **Field of Classification Search**

USPC D10/106.6, 106.7, 70; D16/203

See application file for complete search history.

Primary Examiner — George D. Kirschbaum

(57) **CLAIM**

The ornamental design for movement sensor with camera, as shown and described.

DESCRIPTION

1. Movement sensor with camera

1.1 : Front

1.2 : Back

1.3 : Perspective

Reproduction 1.1 is a front view; reproduction 1.2 is a back view; reproduction 1.3 is a perspective view.

1 Claim, 3 Drawing Sheets
